UNITED STATES PATENT OFFICE.

LEWIS M. STUFFINGS, DECEASED, LATE OF PEORIA, ILLINOIS, BY KATHERINE E. STUFFINGS, ADMINISTRATRIX, OF PEORIA, ILLINOIS.

SHINGLE.

1,417,641.

Specification of Letters Patent. Patented May 30, 1922.

Application filed March 25, 1921. Serial No. 455,635.

To all whom it may concern:

Be it known that LEWIS M. STUFFINGS, formerly a citizen of the United States, residing at Peoria, in the county of Peoria and State of Illinois, now deceased, did invent certain new and useful Improvements in Shingles; I, KATHERINE E. STUFFINGS, of the city of Peoria, county of Peoria, State of Illinois, administratrix of the 10 estate of said LEWIS W. STUFFINGS, deceased, do hereby declare that the following is a full, clear, and exact description of the invention, which will enable others skilled in the art to which it appertains to make and use the same.

This invention relates to improvements in that type of roof covering parts known as shingles, pertaining particularly to shingles made of composition or those manufactured 20 from felt, asbestos, asphalt, and the like.

The purpose of the invention is to mark each shingle at its several edges, as by notching, whereby as each course is laid and without first drawing lines upon the roof as a 25 guide line, as is usually done, the shingles may be applied at once and with perfect regularity, with a saving of much time and labor.

Another purpose or object is to furnish a 30 shingle with a notch or notches in its edges so disposed that in the act of laying a series of at least three of such shingles, the said notches may be made to register with one another whereby a perfectly "lined up" job 35 will result.

The accompanying drawing illustrates the improved shingle and the manner of disposal of several of them with reference to one another.

40 Figure 1 shows one of the shingles as seen in perspective,

Figure 2 is a plan of portion of a roof showing the shingles of the invention placed thereon,

45 Figure 3 is an end elevation of part of a roof structure, and

Figure 4 is a plan of three of the shingles on a larger scale than in Figure 2 showing the manner of registering certain of their 50 notches in the practical laying of a roof according to the invention.

In Figure 1 the numeral 1 indicates a shingle as it is preferred to construct it. At each of its shortest edges or what may be 55 termed its ends the shingle is provided with

a notch 2 whose width corresponds to the distance the shingles are to be spaced from one another when laid in position, the depth of measurement of said notch being purely arbitrary.

Each of the longest edges of the shingles, termed the side edges, is furnished with two notches 3, 4, those at opposite sides, designated by the same numeral, being spaced equi-distant from the ends as most clearly shown in Figure 4. The distance these notches are spaced from the ends of the shingle nearest which they lie corresponds to the extent of surface of shingle to be exposed to the weather, it being observed in 60 said Figure 4 that the notches 4, due to the length of all of the shingles, are disposed at the end notches 2 of the inner ends of two shingles of the group of three shown.

Again, preferably the notches 3, 4 are triangular ones instead of square as are the notches 2. That is to say that edge of the notches 3 and 4 lying nearest the end in which they are formed may be parallel to the shingle-ends, the other edge being cut 65 back or slanted toward the edge of the shingle in the direction of the other end thereof. But these notches and the notches 2 may be of other forms if desired.

In Figures 2 and 3, 5 shows any usual 70 gutter and 6 the line of the roof terminating above it at one side. In laying the shingles, the bottoms of the notches 2 at one of their ends are placed in register with said line 6 giving enough overhang to properly carry 75 the water into said gutter; see the relation 80 shown in Figure 3.

If we suppose the width of said notches 2 to be one-half inch, the shingle of the course of shingles first laid down may be spaced 85 that distance apart.

In superimposing each shingle of the next course the notch 2 at one end is placed in register with the space so left between two shingles in the previous course, so that each 90 side edge of its said notch is in the same plane with the side edges of said two shingles. At the same time the notches 4 will register with the notches 2 of the inner or upper ends of the shingles of the said first 95 course, one of the edges of said notches 4 paralleling a shingle-end, lying in the same plane with the shingle-end, with the side edges of the shingle thus placed in the 100 same plane with one of the side edges of the 105 shingle. At the same time the notches 4 will register with the notches 2 of the inner or upper ends of the shingles of the said first course, one of the edges of said notches 4 paralleling a shingle-end, lying in the same plane with the shingle-end, with the side edges of the shingle thus placed in the 110 same plane with one of the side edges of the

notches 2 as already explained. This arrangement of notches provides for an absolutely exact laying of shingles with no likelihood of the courses being placed otherwise than exactly in line, and without preliminary chalk lines as guides for shingle laying; i. e., the several notches 2, 4, 4, and the advantage of having at least three points on the shingle by which to guide the mechanic, a more perfect job and faster work is the result than where a line is used upon a common wooden shingle parallel to the shingle-end used as a guide with which arrangement I am familiar.

15 The ends of the shingles are identical in appearance so that either end may be used.

What is claimed is:

1. A shingle provided with an indentation at its edge midway the length of one of its shortest sides and having at each of its opposite longest sides an indentation spaced farther from one end than the other for indicating the amount of exposure of the shingle to the weather, the indentations at said 25 opposite sides being each spaced an equal distance from one of the shortest sides of said shingle.

2. A shingle having a notch cut therein midway the width thereof at one of its shortest edges, and having a notch in each of its opposite edges nearest the end remote from that having the first named notch.

3. A shingle having a notch in one of its shortest edges midway of the length of that edge, and also having a notch in each of its longest edges nearest the opposite end of

the shingle, each of the said notches being spaced an equal distance from said end.

4. A shingle having a notch in one of its shortest edges midway the length of that edge, and also having a notch in each of its longest edges each spaced an equal distance from the end of the said shingle remote from that having the first named notch, the distance said notches are spaced from said end corresponding to the length of shingle to be exposed to the weather at its end having said first named notch.

5. A shingle having at each shortest edge thereof a notch midway the length of that edge, and also having a notch in the opposite longer edges thereof each spaced from one end a distance corresponding to the extent of shingle length surface to be exposed to the weather.

6. A shingle having at each shortest edge thereof a notch midway the length of that edge, and also having two pairs of notches disposed opposite one another in the opposite longer edges, each pair of the opposite corresponding notches being spaced a distance from one end of the shingle equal to the extent of shingle length to be exposed to the weather.

In testimony whereof I affix my signature 65 in presence of two witnesses.

KATHERINE E. STUFFINGS,
Administratrix of the estate of Lewis M.
Stuffings, deceased.
